HYDROCARBON CONVERSION PROCESS

Victor J. Anhorn, Oakmont, Meredith M. Stewart, Penn Township, Allegheny County, and Wallace E. Morrow, Allison Park, Pa., assignors to Gulf Research & Development Company, Pittsburgh, Pa., a corporation of Delaware

**No Drawing. Application February 25, 1952,
Serial No. 273,335**

2 Claims. (Cl. 196—50)

This invention relates to catalytic processes for the conversion of normally liquid hydrocarbons, especially hydrocarbons boiling in the gasoline or naphtha boiling range, in the presence of hydrogen.

The more important processes that have been practiced or proposed for the catalytic conversion of hydrocarbons in the presence of hydrogen involve operating under such conditions, including pressures of about 100 to 1500 pounds per square inch and temperatures of at least 700° F., that a carbonaceous material or coke is deposited on the catalyst, which deposit is burned off the catalyst in an oxidative regeneration period of the process. Such processes are advantageous as compared with extremely high pressure processes in which no deposit is formed in the catalyst in that equipment and operating costs (e. g. cost of compressing gases and the like) are lower and the products are improved products. Processes of this type include operations wherein a relatively heavy liquid hydrocarbon or mixture of hydrocarbons such as a gas oil, whole crude, reduced crude, coke still distillate, and the like, is contacted with a catalyst in the presence of hydrogen under these elevated temperature conditions, preferably temperatures of about 800° to 1100° F. In this type of process the hydrocarbons are subjected to hydrocracking which involves scission of carbon to carbon bonds, dehydrogenation, hydrogenation and related changes in structure of the hydrocarbons. Also, some desulfurization occurs in every case and excellent desulfurization takes place with the use of selected catalysts.

Another type of conversion process carried out in the presence of hydrogen is employed for the treatment of hydrocarbons boiling in the gasoline or naphtha boiling range and may be referred to as catalytic reforming in the presence of hydrogen or "hydroreforming." In this process the objective is primarily to accomplish isomerization and aromatization of the hydrocarbons making up the charge and consequent increase in the octane number of the product. In this type of operation there is ordinarily very little difference between the average molecular weight of the charge and that of the product although some cracking may occur, particularly under high conversion conditions. The temperature employed in catalytic reforming in the presence of hydrogen is in excess of 700° F., a temperature of about 800° to 1100° F. generally being preferred, and the pressure should be about 100 to 1000 pounds per square inch. A version of this process is generally referred to as hy-

2

droisomerization. The charge to a hydroisomerization process is largely paraffinic and may consist of a single normal paraffin such as normal pentane or normal hexane. The principal result here is to convert the normal paraffins to isoparaffins.

As stated previously, processes of these types are carried out at pressures which may vary from about 100 to about 1500 pounds per square inch. The hydrogen pressure maintained in the reaction zone has an effect upon the type of conversion taking place, other conditions being maintained constant. The maintenance of high hydrogen pressures within this range is generally effective to permit conversion with longer on-stream periods. When lower hydrogen pressures within this range are used, the conversion involves a more rapid formation of a carbonaceous deposit on the catalyst. Such processes, therefore, comprise a cyclic operation in which frequent regeneration is necessary.

The catalysts that have been employed for the conversion of hydrocarbons in the presence of hydrogen comprise a recognized class. These catalysts are referred to as hydrogenation catalysts and include one or more of the metals of Groups V, VI, and VIII of the Periodic Table and the oxides of these metals. The more important of these metals are chromium, molybdenum, tungsten, cobalt and nickel. While these metals or metal oxides may be used alone, for example in the form of gels, it is the usual practice to employ catalysts which comprise one or more of these metals or metal oxides deposited on a suitable support such as activated alumina, kieselguhr, silica-alumina composites containing a major proportion of silica, activated clays, and the like. A particularly valuable support is an activated alumina containing a relatively small amount of silica, for example about 5 per cent by weight, which serves to improve the surface characteristics of the support.

We have discovered in accordance with the invention that improved results can be obtained by carrying out a process for the conversion of hydrocarbons as above described in the presence of a catalyst of the above class in which at least a part of the metal is in the form of the nitride. The nitrides of these metals can be prepared by separately contacting the catalyst with a nitriding agent, preferably ammonia, at an elevated temperature. While it is not necessary to convert all of the metal to the nitride in order to achieve the advantages of the invention, the nitriding operation should be carried out in such manner as to convert at least 25 per cent, and preferably at least 50 per cent, by weight of the metal in the catalyst to the nitride form. The metal nitrides are relatively stable and will continue to be effective during a normal on-stream period. It is preferred in most cases to nitride the catalyst after oxidative regeneration to insure that an important part of the metal in the catalyst is in the nitride form at the beginning of the reaction period.

The effect of the nitriding treatment is in general to increase the activity of the catalyst, although the specific result of this increase in activity will vary depending upon the type of conversion operation in which the catalyst is used, the particular catalyst employed and other factors. For example, the hydrocracking activity of a

catalyst is improved by nitriding where the charge stock is a heavy hydrocarbon mixture. In hydroreforming, a higher octane product is obtained with the use of a nitrided catalyst than is obtained with the use of the untreated catalyst at the same conditions. The effect of the nitriding treatment is especially noticeable when conditions adapted to result in high conversion of the charge are maintained.

In accordance with a preferred embodiment of the invention, a naphtha fraction of petroleum is subjected to hydroreforming in the presence of a nitrided hydrogenation catalyst. While any of the hydrogenation catalysts are more or less satisfactory for this process, a preferred catalyst is one consisting of molybdena deposited on an activated alumina support and preferably such a support containing about 5 per cent by weight of silica. Ordinarily, the molybdena, consider to be MoO_3 , constitutes about 8 to 12 per cent by weight of the finished catalyst. Depending upon the specific results that are desired to be obtained, such as the length of the process period, the pressure employed may be from about 100 to about 1000 pounds per square inch. Within this pressure range the length of the on-stream period can be varied by varying the pressure and the hydrogen recycle rates. When using the catalyst referred to above to obtain a high octane product, the conversion is preferably carried out at a temperature within the range of about 850° to about 950° F. These conditions result in a net production of hydrogen in the reaction zone. The hydrogen introduced into the reaction zone and formed in that zone is separated from the product and at least a part is recycled to the reaction zone. The charge to the reaction zone should comprise about 1,000 to 10,000 standard cubic feet (s. c. f.) of hydrogen per barrel of naphtha charged and preferably about 1,000 to about 5,000 s. c. f.

The operating cycle for this process preferably comprises (1) reducing the catalyst with hydrogen, (2) nitriding the catalyst, (3) the reaction period, (4) purging the catalyst, and (5) regenerating the catalyst by burning off the carbonaceous deposit formed in the reaction period. The step of reducing the catalyst with hydrogen can be omitted; however, in such case more nitriding agent is required to convert the same amount of the catalytic metal to the nitride. When reduction is practiced the catalyst is reduced with hydrogen at an elevated temperature, for example at a temperature of the order of 700° to 1100° F. and preferably about 900° to 1000° F., at reaction pressure or at a lower pressure. It is preferred to reduce at atmospheric pressure. This reducing operation is continued for a time sufficient to convert at least a substantial proportion of the MoO_3 to MoO_2 , which is usually about 1 to 5 hours in the preferred temperature range. The reduced catalyst is then nitrided, preferably by contacting it with ammonia at an elevated temperature. The nitriding temperature should be within the range of about 700° to 1100° F. and preferably about 900° to about 1000° F. The nitriding operation is continued until at least 25 per cent, and preferably at least 50 per cent by weight of the molybdenum is present in the form of the nitride, which ordinarily requires about 1 to 5 hours under the preferred conditions. Lower temperatures can be employed in this nitriding treatment but are not preferred because a longer treating time is required. Following the nitriding treatment, the naphtha charge and hydrogen are contacted with the catalyst under the reaction conditions outlined above until the quality of the product falls below a selected level. The catalyst is then purged to remove occluded hydrocarbons and hydrogen and is subjected to oxidative regeneration. The regeneration is preferably accomplished by contacting the catalyst with air or another oxygen-containing gas. The regenerated catalyst is then in condition for the reducing treatment described above.

The hydroreforming process as described can be carried out with the catalyst deposited in a stationary fixed bed, in which case the catalyst is usually employed in the form of granules or pellets. When using the catalyst in a fixed bed, the above cycle of operations is carried out on the catalyst in the reaction zone. Inasmuch as the reaction is endothermic, provisions are made for supplying heat to the catalyst bed during the reaction period.

This process may also be carried out utilizing the catalyst in fluidized state. In this operation a finely divided catalyst is employed. While the above cycle of operations may in this case also be carried out on the catalyst while the catalyst is in the reaction zone, it is generally preferred to provide a separate regenerator to which catalyst from the reactor may be conveyed either periodically or continuously. The regeneration may be accomplished at about the pressure in the reactor or at about atmospheric pressure. When the regeneration is carried out in a vessel separate from the reactor, the steps of reducing the catalyst with hydrogen and contacting the catalyst with a nitriding agent should preferably be conducted in a vessel into which the catalyst from the regenerator is introduced.

In order that the invention may be understood more fully, the following specific example will be described. This example is concerned with the hydroreforming of a West Texas straight run naphtha having the following characteristics:

45 The catalyst employed consisted of about 11 weight per cent molybdenum oxides calculated as MoO_3 and a finely divided activated alumina base which contained about 5 per cent silica. The cycle of operations involved in hydroreforming was carried out on this catalyst disposed in a fixed fluidized bed under the conditions set out in the following Table I. The catalyst, initially in oxidized form, was first reduced by contacting it with hydrogen at atmospheric pressure and a temperature of about 950° F. In this operation a hydrogen gas space velocity (volumes of hydrogen at standard temperature and pressure/volume of catalyst/hour) of 620 was maintained for five hours. The catalyst was then nitrided by contacting it with ammonia gas at a space velocity of approximately 500 (volumes of ammonia gas at standard temperature and pressure/volume of catalyst/hour), at a temperature of about 950° F. and a pressure of 5 pounds per square inch gauge for a period of three hours. Another batch of the same molybdena-alumina catalyst was also employed in the hydroreforming of this naphtha. This batch was treated as described above except that the nitriding treatment was omitted. In carrying out hydroreforming of the naphtha using these catalysts, the temperature in the first part of each run was maintained at about 875° F., the product obtained in operation at this temperature for the throughput interval indicated in Table I was collected and thereafter the temperature was raised to about 900° F. and the product from the indicated throughput interval at this higher temperature was separately collected. The results obtained are apparent from the data given in the following Table I.

The results given in this table show that the nitriding of the catalyst substantially increased its activity in the hydroreforming process. Thus, considering the 10 lb. vapor pressure-C₃ free gasoline containing 3 ccs. of tetraethyl lead per gallon produced in Period A, it will be seen that the octane number of the gasoline was 91.5 whereas the octane number of the gasoline produced in comparable Period C, using the nitrided catalyst, was 96.2. Similarly, in the operations carried out at about 900° F. and somewhat above, the octane number of the gasoline in the case of the untreated catalyst was 90.8, whereas the octane number of the gasoline obtained when using the nitrided catalyst was 98.5, despite the fact that the temperature was higher in the period using the untreated catalyst.

In another set of runs, a West Texas naphtha was subjected to hydroreforming in the presence of a molybdena-alumina catalyst of the type employed in the runs described in Table I. This catalyst had been regenerated and was in the fully oxidized state. One batch of it was nitrided without a prior reducing treatment; i. e., the nitriding was carried out on a catalyst in which the molybdenum was present at least largely in the form of MoO₃. The nitriding treatment consisted of passing NH₃ in contact with the catalyst for three hours at a temperature of about 1050° F. and a pressure of about 50 pounds per square inch gauge. Another batch of the same regenerated catalyst was reduced by contacting it with hydrogen for three hours at a temperature of about 1050° F. and a pressure of about 50 pounds per square inch gauge. The naphtha charge was contacted in separate runs with these two catalysts under conditions similar to those described previously except that the temperature was about 900° F., the pressure about 800 pounds per square inch gauge, and the charge rate (weight of charge per weight of catalyst per hour) was 2.0. It is noted that the charge

rate used in the runs, the results of which are set out in Table I, was about 1.0. Accordingly, the conversion conditions were milder in the present runs than those of the previously described runs. The results and the inspection data are given in Table II.

45 It will be noted by comparing the results of Period E carried out on the reduced and unnitrided catalyst with the results of Period G in which the nitrided catalyst was employed, that the octane numbers of the product obtained in Period E are substantially lower than those obtained in Period G. It will also be noted that with longer operation the results obtained on the two catalysts tend to become the same. This indicates that the activity of the nitrided catalyst is especially good at low throughputs. Accordingly, if these data are considered 50 in connection with a continuous hydroreforming operation where the oil to catalyst ratios might vary from say 5:1 to 1:1 whereas the oil/catalyst ratio for a throughput of 10 is 10:1, the data indicate that the effect of the nitriding treatment should be even more pronounced in such 55 an operation than is indicated by the data given in the table.

60 It will be understood that the foregoing examples are merely illustrative of the invention and that comparable results can be obtained by using nitrided hydrogenation catalysts in other processes for the conversion of hydrocarbons in the presence of hydrogen. As will be seen from the results obtained in the above examples, it is not necessary to subject the catalyst to a hydrogen reducing treatment prior to nitriding as it appears only 65 necessary in order to obtain the advantages of the invention to convert a substantial proportion of the metal of the catalyst to the nitrided form. Because ammonia is readily available and easy to use, it is the preferred nitriding agent. However, a wide variety of non-oxidizing 70 ing nitrogen-containing compounds which are in vapor

form at nitriding temperatures can be used in place of this material, although in many cases higher nitriding temperatures or longer periods of treatment are required to obtain the same conversion of the metal to the nitride form. As examples of such nitrogen-containing compounds there may be mentioned hydrogen cyanide, organic nitriles, organic amines, and nitrogen itself. Where the nitriding agent is itself not a reducing agent, such as is ammonia, it is necessary to accomplish some reduction of the catalyst prior to nitriding. The nitriding treatment goes smoothly with the use of ammonia, and a promoter is not necessary, but promoters can be employed if desired. Thus, for example, the catalyst may be lightly impregnated with a lithium compound before beginning the nitriding treatment. In view of the fact that the catalytic metal is converted to the metal nitride in the present process whether the metal of the catalyst is in the metal form or the oxide form prior to the nitriding treatment (thus either molybdenum metal or molybdenum oxide is believed to be converted to Mo_2N), where a catalyst comprising a metal is referred to in the claims, it will be understood that the oxides as well as the free metals are included.

With respect to the hydrogen concentration that should be employed in the present process, it will be understood that the optimum concentration in each case will vary depending upon the particular operation being carried out, but there must be sufficient hydrogen to make the operation what might be termed a hydroconversion process. Thus, the hydrogen concentration should be about 1,000 to 30,000 standard cubic feet of hydrogen per barrel (42 U. S. gallons) of charge hydrocarbons.

Obviously many modifications and variations of the invention as hereinabove set forth may be made without departing from the spirit and scope thereof and therefore only such limitations should be imposed as are indicated in the appended claims.

We claim:

1. A process for hydroreforming naphtha which comprises contacting said naphtha under hydroreforming conditions including temperature of about 850° to 950° F., pressure between about 100 and 1000 pounds per square inch and hydrogen concentration of about 1000 to 10,000 standard cubic feet of hydrogen per barrel of said hydrocarbons with a molybdenum catalyst supported on activated alumina in which at least 25 per cent by weight of the molybdenum is in the form of the nitride, said catalyst having been prenitrided by separately contacting it with a vaporized nitriding agent at a temperature above 700° F. until at least 25 percent by weight of the molybdenum is in the form of the nitride.
15. 2. A process for hydroreforming naphtha which comprises contacting said naphtha under hydroreforming conditions including temperature of about 800° to 1100° F., pressure of about 100 to 1000 pounds per square inch and hydrogen concentration of about 1000 to 10,000 standard cubic feet of hydrogen per barrel of said hydrocarbons with a prenitrided molybdenum catalyst supported on activated alumina, said catalyst having been prenitrided by separately contacting it with ammonia at temperature of about 900° to about 1000° F. for about 25. one to five hours.
